REFRIGERATING APPARATUS

Leroy W. Shultz, Detroit, Mich., assignor to
Frigidaire Corporation, Dayton, Ohio, a cor-
poration of Delaware

Application October 31, 1931, Serial No. 572,382

1 Claim. (Cl. 62—115)

This invention relates to refrigerating apparatus and specifically to refrigerating apparatus particularly adaptable to be used in conjunction with vehicles.

The primary object of the invention is to provide a refrigerating system or apparatus for a vehicle which utilizes the medium through which the vehicle is driven for causing operation of the refrigerating apparatus.

Further objects and advantages of the invention will be apparent from the following description, reference being had to the accompanying drawing, wherein a preferred form of the present invention is clearly shown.

In the drawing:

Fig. 1 discloses a somewhat diagrammatical view of a refrigerating system constructed and applied to an airplane in accordance with my invention;

Fig. 2 is a sectional view taken on the line 2—2 of Fig. 1 showing the arrangement of a condenser in a housing through which air is caused to flow; and

Fig. 3 is a view, taken in the direction of the arrow designated at 3 in Fig. 1, of the means for driving the compressor and the housing in which certain elements of a refrigerating system are located.

In carrying out the object of my invention I make use of a compressor-condenser-expander type refrigerating system and I provide means whereby the liquefying unit of said system is operated economically and efficiently by the flow of air past the vehicle in which the system is installed.

Referring now to the drawing and particularly to Fig. 1 I have disclosed for the purpose of illustrating my invention a portion 10 of the body of an airplane or the like of any suitable construction and having an insulated cabinet 11 positioned in the body portion 10 of the airplane and preferably in the galley thereof. The cabinet 11 is utilized to store comestibles or the like which are to be cooled and served or served direct from the cabinet for consumption by the individuals being transported by the airplane. Since these comestibles are desired to be maintained in a fresh condition and since they must be prevented from deteriorating or spoiling I dispose an evaporator or cooling unit 15 of a refrigerating system in the cabinet 11. The evaporator 15 is operatively connected with a refrigerant liquefying and circulating unit including a compressor 16, a condenser 17 and a liquid refrigerant receiver 18. The method of producing refrigeration in the evapora-

tor 15 during operation of the refrigerating system is conventional and comprises evaporating refrigerant of the system in the evaporator 15, withdrawing the evaporated refrigerant therefrom through conduit 19 by the compressor 16 69 and again compressing the same, circulating the compressed refrigerant through the conduit 21 to the condenser 17 for cooling and liquefying the same. The liquid refrigerant is then stored in liquid receiver 18 preparatory to being again circulated to evaporator 15 through the conduit 22. An expansion valve 23 of any suitable construction which is throttled or actuated into open or closed position by a thermostat 24 responsive to the temperature of the evaporator 15 is employed 70 to automatically admit liquid refrigerant, when required, from the conduit 22 to the evaporator 15 for maintaining the evaporator at a substantially uniform low temperature.

Compressor 16, condenser 17 and receiver 18 75 are all disposed on the exterior of the body portion 10 of the airplane and are mounted in any suitable manner in a casing 26. This casing 26 is shown as mounted on the body portion 10 of the airplane but it is to be understood that it can be 80 located on a wing of the airplane or wherever desired. Casing 26 is formed into a cigar-shape so as to have a so-called "stream line" appearance which offers a minimum of resistance when being moved through the medium traversed by the 85 vehicle or airplane. In order to provide for economical operation of the refrigerating system and particularly the operation of compressor 16 I mount the compressor 16 in or at the front portion of the casing 26 and form the walls of the 90 compressor to correspond to the general outline of the casing 26.

Compressor 16 can be of any suitable design for instance it may be of the reciprocal type or it may be of a gear or rotary vane type. Irrespective of the particular construction of the compressor, suitable for use in my apparatus all such compressors usually include some sort of a drive shaft. In the present embodiment of the invention the compressor includes a drive shaft 28 extending therefrom and connected with the refrigerant compressing means within the compressor (not shown). A means for operating the compressor 16 is provided in the form of a propeller or fan 29 secured to the compressor drive shaft 28. The propeller or fan 29 is adapted to be actuated by the movement of a fluid such, for example, as air in the embodiment shown and described. The fan 29 operates the compressor during movement 100 of air thereover which obviously occurs while the 105

110

airplane is being flown. The condenser 17 may likewise be of any suitable construction and is arranged preferably within the casing 26. Casing 26 has a plurality of louvers or openings 31 formed 5 in its top portion and a plurality of similar louvers or openings 32 formed in its bottom wall portion. The condenser 17 is positioned within the casing 26 so as to be in the path of air moving over and through the propeller or fan 29 and circulated into 10 the casing 26 to the louvers 31. The air after traversing the condenser 17 flows from the casing 26 through the louvers 32 in the bottom wall thereof.

The compressor 16 is obviously operated continuously by the propeller or fan 29 as long as the 15 airplane is in flight but it does not continuously compress refrigerant contained in the system unless the temperature of the evaporator 15 is above the desired limit and expansion valve 23 is open. 20 Such continuous operation of the compressor if not compressing refrigerating liquid merely creates a vacuum in the evaporated refrigerant conduit or low pressure line 19 of the refrigerating system. Compressor 16 may have an un- 25 loader, of any conventional type or design, incorporated therein or connected thereto and actuated when the vehicle or airplane is stopped for a considerable length of time. The use of the unloader is obviously desirable to those skilled in 30 the art for the purpose of equalizing the pressures between the high and low pressure sides of the refrigerating system so that the propelling means for the compressor can be put in motion under less resistance. Consequently the refrigerating system may begin operating as soon as 35 the vehicle or airplane is put into motion.

From the foregoing it is apparent that the medium through which the vehicle or airplane travels is utilized for a two-fold purpose, that is, 40 the medium is employed to drive the compressor and to cool the condenser of the refrigerating ap-

paratus. Thus the refrigerating apparatus needs no artificial source of power such as a motor for driving the compressor which motor must be supplied with power from a source of energy such, for example, as a storage battery or a generator. 80 Therefore the apparatus for producing refrigeration in the vehicle or airplane is simplified and reduced in elements and consequently the weight thereof is minimized thus reducing the load carried by the vehicle or airplane. It is also apparent that my invention provides a refrigerating system which is economical in operation and which will readily start operating when the vehicle or airplane is put into motion after stopping at designated terminals or the like for considerable lengths of time. 90

While the form of embodiment of the invention as herein disclosed constitutes a preferred form, it is to be understood that other forms might be adopted, all coming within the scope of the claim 95 which follows.

What is claimed is as follows:

Refrigerating apparatus comprising in combination, a vehicle including a body having an insulated compartment therein to be refrigerated, 100 an evaporator of a closed refrigerating system disposed in said compartment for cooling the same, a condenser connected to said evaporator, a compressor exteriorly of said vehicle body and operatively connected to said evaporator and to 105 said condenser, means operated by the air through which the vehicle passes for driving the compressor, a torpedo-shaped or stream-lined casing exteriorly of said vehicle body and enclosing said condenser, said casing having air inlet 110 openings in one wall thereof and air outlet openings in another wall thereof for permitting the air through which the vehicle passes to flow through said casing and over said condenser. 115
